CLAIM

I claim the ornamental design for a control module for a modular, stackable energy storage system, as shown and described.

DESCRIPTION

The subject matter of this application relates generally to the subject matter disclosed by U.S. patent application Ser. No. 16/443,266, “Modular Battery Pack System with Multivoltage Bus,” filed on Jun. 17, 2019.

FIG. 1 is an isometric view of a control module for a modular, stackable energy storage system showing our new design from the top, front and side.

FIG. 2 is a front side elevation view of the control module.

FIG. 3 is a rear side elevation view of the control module.

FIG. 4 is a side elevational view of the control module.

FIG. 5 is a side elevational view of the control module, shown from the side opposite the side shown in FIG. 4.

FIG. 6 is a top side view of the control module.

FIG. 7 is a bottom side view of the control module; and,

FIG. 8 is an isometric view of the control module, shown in an environment of use stacked on top of first and second battery modules.

The broken-line showing of the control module in the drawings is for the purpose of illustrating environmental structure and forms no part of the claimed design.
